US0D1057724S

(12) **United States Design Patent** (10) Patent No.: **US D1,057,724 S**
(45) Date of Patent: ** Jan. 14, 2025

(54) **BASE FOR DETACHABLE DISPLAY DEVICE**

(71) Applicant: **Google LLC**, Mountain View, CA (US)

(72) Inventors: **Bengt Gunnar Brümmer**, San Francisco, CA (US); **Maj Isabelle Olsson**, Sunnyvale, CA (US); **Carl Cepress**, Los Altos, CA (US); **Vicki Huichi Chuang**, Santa Clara, CA (US); **Ethan Alexander Graves**, Santa Clara, CA (US); **Casey Gardner Peterson**, Scotts Valley, CA (US); **Wenson Chern**, San Jose, CA (US); **Andrew Zee**, San Francisco, CA (US)

(73) Assignee: **Google LLC**, Mountain View, CA (US)

(**) Term: **15 Years**

(21) Appl. No.: **29/838,017**

(22) Filed: **May 10, 2022**

(51) LOC (15) Cl. **14-03**

(52) U.S. Cl.

USPC **D14/447**

(58) **Field of Classification Search**

CLAIM

The ornamental design for a base for detachable display device, as shown and described.

DESCRIPTION

FIG. 1 is a top, front, right side perspective view of a base for detachable display device showing our new design;

FIG. 2 is a top, rear, right side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings depict portions of the base for detachable display device that form no part of the claimed design.

1 Claim, 5 Drawing Sheets
